OIL BURNER NOZZLE

Cecil R. Waldron, Bloomington, Ill., assignor to
 Eureka Williams Corporation, Bloomington, Ill.,
 a corporation of Michigan

Application April 21, 1948, Serial No. 22,379

3 Claims. (Cl. 299—120)

1

This invention relates to fuel and air mixing nozzles adapted for use in forming a primary mixture to be burned in a blast of secondary air, such nozzles being useful particularly in connection with low-pressure type oil burners.

An object of the invention is to provide a better and a more quiet and efficient nozzle for use in connection with the formation of a primary mixture in low pressure type oil burners.

Other and further objects of the invention will be apparent by reference to the accompanying drawings of which there is one sheet, which, by way of illustration, shows a preferred embodiment and the principles thereof and what I now consider to be the best mode in which I have contemplated applying these principles. Other embodiments of the invention embodying the same or equivalent principles may be used and structural changes may be made as desired by those skilled in the art without departing from the present invention and the purview of the appended claims. I also contemplate that of the several different features of my invention, certain ones thereof may be advantageously employed in some applications separate and apart from the remainder of the features.

In the drawing:

Fig. 1 is a fragmentary view illustrating an oil burning furnace employing a low-pressure type oil burner having a primary fuel and air mixing nozzle embracing the principles of the invention;

Fig. 2 is an enlarged longitudinal sectional view of a part of the primary fuel and air mixing nozzle embraced in the structure disclosed by Fig. 1;

Fig. 3 is a cross sectional view through the fuel and air mixing nozzle illustrated by Fig. 1. Fig. 3 is taken substantially in the plane of line 3—3 of Fig. 1; and

Fig. 4 is another cross sectional view through the nozzle illustrated by the preceding figures, except that Fig. 4 is taken substantially in the plane of line 4—4 of Fig. 2 with the forward end of the inner tubular body embraced in the nozzle shown in end elevation.

Referring particularly to Fig. 1, the numeral 10 indicates generally an oil burning furnace having a combustion chamber 11 which is surrounded by a wall 12 having an opening 13 formed therein for the reception of an air cone or nozzle member 14 through an orifice 16 in which a blast of secondary air is supplied to the combustion chamber 11. Disposed outwardly of

2

the orifice 16 and concentrically relative thereto is a primary fuel and air mixing nozzle 17 having an orifice 18 formed concentrically within the front end thereof and through which ori-
 5 fice a blast consisting of a primary mixture of fuel and air is discharged into the combustion chamber 11 concentrically with respect to the blast of secondary air supplied by the orifice 16. The nozzle 17 consists of an outer tubular body or member 19 having a front wall 21 in which the orifice 18 previously referred to is formed.

The inner surface of the wall 21 is frusto-conical in formation, as is indicated at 22, the orifice 18 being formed at the smaller end of the surface 22 which forms a knife edge around the periphery of the orifice 18.

Rearwardly of the surface 22, the interior of the body 19 is of cylindrical formation as is indicated at 23, the cylindrical surface 23 being
 20 adapted to receive and to closely fit the exterior cylindrical surface 24 of an inner tubular body 26. The forward end of the inner tubular body 26 is provided with an annular frusto-conical seat indicated at 27 which is adapted to engage the
 25 surface 22 at the base thereof to provide within the front end of the outer body 19 a tip chamber 28 communicating with the orifice 18.

Within the annular seat 27 the forward end of the inner body 26 is provided with a planular
 30 annular surface indicated at 29 and from the central portion of which a conical tip indicated at 31 projects toward the orifice 18 in concentric relation thereto.

Beyond the annular seat 27 the inner body 26
 35 has formed within the exterior cylindrical surface thereof a plurality of longitudinally disposed channels or air and fuel mixing chambers indicated by the numeral 32. The inner surfaces of the chambers or channels 32 are plane surfaces
 40 which extend in opposite directions toward the inner cylindrical surface 23 of the outer body 19 and at the ends of which are paralleled channel side walls, the outer edges of which terminate in the exterior cylindrical surface 24 of the inner body 26. Between the channels 32 which are equally spaced about the circumference
 45 of the inner body 26, the exterior cylindrical surface of the inner body 26 provides a plurality of longitudinally disposed arcuate seats indicated at
 50 33 which engage and form a relatively fluid tight fit with the inner cylindrical surface 23 of the outer body 19. The forward ends of the fuel and air mixing chambers 32 terminate at the seat 27 and are connected with the tip chamber 28 across

the seat 27 by angularly disposed passages 34 which are formed in the front end of the inner tubular body 26.

The cross section of the passages 34 is not as great as the cross section of the air and fuel mixing chambers or channels 32, so as to increase the velocity of the primary fuel and air mixture to be formed in the chambers 32 as this mixture moves through the passages 34 from the chambers 32 to the tip chamber 28. The passages 34 are eccentrically related to the end of the inner tubular body 26 and the tip chamber 28, the forward ends of the passages 34 terminating within the tip chamber 28 within the annular surface 29 and in eccentric relation to the tip chamber 28. The rear ends of the passages 34 also terminate in the forward ends of the chamber 32 in eccentric relation to the latter chambers and midway between the side walls thereof.

The inner body 26 is provided with a liquid fuel supply passage 36 formed internally and toward the front end thereof, the passage 36 being connected to the chambers 32 intermediate the ends thereof by a plurality of radially disposed fuel supply ports 37. The outer ends of the ports 37 which terminate within the central portions of the channels 32 are formed with relatively sharp edges so as to tend to divide and to atomize fuel which may be discharged from the ports 37 into the air which moves forwardly within the channels 32.

Air at a relatively low pressure is adapted to be supplied to the channels 32 by a conduit 38 which projects from the casing 39 of a low pressure type oil burner which is provided with a pumping unit adapted to supply fuel and air to the nozzle 17 at approximately the same pressures. The oil burner also is provided with a fan for supplying secondary air which is discharged into the combustion chamber 11 through the orifice 16. For a more complete description of an oil burner system of this type and the primary and secondary air and the fuel pumping, metering and fan mechanism employed therein, reference may be had to the co-pending applications for United States Letters Patent of Howard E. Earl, Serial No. 2,881, filed January 17, 1948, for Oil Burner System, now Patent No. 2,554,491, issued May 29, 1951; Howard E. Earl, Serial No. 772,970, filed September 9, 1947, for Motor Compressor Unit, now Patent No. 2,542,121; and Robert R. Witherell, Ser. No. 13,718, filed March 8, 1948, for Oil Burner Pumping Unit.

The nozzle 17 is removably secured to the threaded end of the conduit 38 by a coupling member 41. Within the conduit 38 and also connected to the oil burner pumping unit referred to is an oil supply conduit 42 which supplies oil to the cavity or passage 36 of the nozzle 17 through a tube 43. The tube 43 is removably positioned at its opposite ends within the cavity 36 and the interior of the conduit 42. Surrounding the tube 43 is a spring 44 which engages the adjacent ends of the conduit 42 and the inner body 26, this spring being adapted to resiliently position the inner body 26 within the outer body 19 with the annular seat 27 in engagement with the front wall 21 of the outer body 19.

The volume of the primary air supplied by the conduit 38 is several times the volume of fuel supplied by the conduit 42, the ratio between these quantities of fuel and air being

whatever ratio may be desired to produce the primary mixture required.

From the conduit 38 the air supplied to the fuel and air mixing chambers 32 moves forwardly within the mixing chambers toward the passages 34. As the air passes over the sharp outer ends of the ports 37 the air picks up and moves along the interior surfaces of the chambers 32 the quantity of fuel required for producing the primary mixture. The fuel and air so proportioned moves forwardly from the ports 37 at approximately the velocity of the air supplied to the opposite ends of the chambers 32 until the forward ends of these chambers are reached. In such regions the fuel and air mixture in the chambers 32 passes over the edges defining the rear extremities of the passages 34, thereby further tending to divide and to atomize the fuel content of the mixture. Due to this reduced cross section of the passages 34, the mixture so described as moving forwardly within the chambers 32 increases in velocity in the passages 34 thereby tending to increase the atomization of the fuel and air mixture and to prevent a separation of the fuel from the air before the mixture is discharged into the tip chamber 28. Owing to the eccentric relation between the passages 34 and the chambers 32 and 28, the mixture from the passages 34 is discharged into the tip chamber 28 in such manner as to rotate the fuel and air mixture within the tip chamber 28. From the tip chamber 28 the mixture is discharged over the knife edges of the orifice 18 in a blast of fuel and air which moves forwardly through the orifice 16 into the combustion chamber 11 in concentric relation to the secondary air also discharged in a blast through the orifice 16. During the discharge of the oil and air mixture from the orifice 18, the conical tip 31 which projects within the orifice serves the purpose of preventing the formation of large drops of oil in the nozzle during the operation thereof. The tip 31 which projects into the orifice 18 progressively increases the velocity of the oil and air mixture as it approaches and passes over the knife edge of the orifice 18, thus causing a finer break-up of the fuel oil particles as the mixture is discharged from the orifice 18 and into and through the orifice 16.

It will be noted that the slope of the surface of the tip 31 is greater than the slope of the surface 22 forming the inside of the front end 21 of the body 19. Under such circumstances the cross sectional area of the tip chamber 28 therefore decreases from the front end of the body 26 to the knife edge orifice 18. Under such circumstances, the rotating body of fluid forming the mixture in the tip chamber 28 will increase in velocity as it approaches the knife edge orifice 18 and the apex of the tip 31.

The relation between the cross sectional area of the air supply and mixing chambers 32, the eccentric passages 34, and the size and shape of the tip chamber 28 is such that the velocity of the fluid in these chambers as it moves toward the knife edge orifice 18 progressively increases.

Beyond the nozzle 17 the primary air and fuel and the secondary air mixture so formed may be ignited by electrodes indicated at 46 for forming a suitable fire within the combustion chamber 11.

When the oil burner controls are operated in such manner as to discontinue the supply of fuel and air delivered to the nozzle 17 by the conduits

38 and 42, the conical tip 31 within the tip chamber 28 will tend to collect and to prevent the discharge from the orifice 18 of any large drops of fuel which otherwise might drip from the end of the nozzle 17.

While I have illustrated and described a preferred embodiment of my invention, it is understood that this is capable of modification, and I therefore do not wish to be limited to the precise details set forth, but desire to avail myself of such changes and alterations as fall within the purview of the following claims.

I claim:

1. An oil burner nozzle comprising an outer tubular body having a circular sharp edged orifice formed coaxially therewith at the front end thereof, an inner tubular body within said outer body and having a front end formed to provide an annular seat disposed in engagement with said outer body and being spaced from said outer body at the front side of said seat to provide a tip chamber communicating with said orifice, said front end of said inner tubular body having a conical tip disposed within said tip chamber and projecting toward said orifice concentrically with respect thereto, said inner body on the side of said annular seat remote from said tip chamber being formed to provide a plurality of seats engaging the interior of said outer body and a plurality of longitudinally disposed air supply and mixing chambers between said seats, one of said bodies being formed to provide a plurality of passages across said annular seat extending between said air supply and mixing chambers and said tip chamber, said passages being of less cross-sectional area than said air supply and mixing chambers and being formed in sloped relation to said air supply and mixing chambers and said tip chamber with the forward ends of said passages terminating within said tip chamber and the rearward ends thereof terminating in said air supply and mixing chambers, said passages being disposed in directions eccentrically of said tip chamber so that said passage ends open into said tip chamber in a direction for inducing the rotation of fluid in said tip chamber, a plurality of spaced oil supply ports extending between the interior of said inner tubular body and said air supply and mixing chambers and through which oil supply ports oil is supplied to said mixing chambers, the outer ends of said ports forming relatively sharp edges across said latter chambers facing the direction of flow of fluid in said latter chambers, said air supply and mixing chambers supplying air for mixture with the oil supplied through said oil supply ports.

2. An oil burner nozzle comprising an outer tubular body having a circular sharp edged orifice formed coaxially therewith at the front end

thereof, an inner tubular body within said outer body and having a front end formed to provide an annular seat disposed in engagement with said outer body and being spaced from said outer body at the front side of said seat to provide a tip chamber communicating with said orifice, said inner body on the side of said annular seat remote from said tip chamber being formed to provide a plurality of seats engaging the interior of said outer body and a plurality of longitudinally disposed air supply and mixing chambers, said inner body being formed to provide a plurality of passages across said annular seat between said air supply and mixing chambers and said tip chamber, said passages being of less cross-sectional area than said air supply and mixing chambers and being formed in sloped relation to said air supply and mixing chambers and said tip chamber with the forward ends of said passages terminating in equally spaced relation within said tip chamber and the rearward ends thereof terminating in said air supply and mixing chambers, said passage ends opening into said tip chamber in a direction related to said tip chamber for inducing the rotation of fluid in said tip chamber, a plurality of spaced oil supply ports extending between the interior of said inner tubular body and said air supply and mixing chambers and through which oil under pressure is supplied to said air supply and mixing chambers, the outer ends of said ports forming relatively sharp edges across said latter chambers facing the direction of flow of fluid in said latter chambers, said air supply and mixing chambers supplying air under pressure for mixture with the oil supplied through said oil supply ports.

3. A nozzle according to claim 1 wherein the relation between the cross sectional area of the air supply and mixing chambers, said passages and the size and shape of the tip chamber is such that the velocity of the fluid progressively increases as it moves toward the knife edge orifice.
